UNITED STATES PATENT OFFICE.

ARTHUR F. REED, OF ROCHESTER, NEW YORK, ASSIGNOR TO F. E. REED GLASS COMPANY, OF ROCHESTER, NEW YORK, A CORPORATION OF NEW YORK.

DESIGN FOR A BOTTLE.

Application filed June 1, 1925. Serial No. 13,620. Term of patent 14 years.

To all whom it may concern:

Be it known that I, ARTHUR F. REED, of Rochester, in the county of Monroe and State of New York, have invented a new, original, and ornamental Design for Bottles, of which the following is a specification, reference being had to the accompanying drawing, forming a part hereof.

Figure 1 is a side elevation of a bottle made in accordance with the invention, and Figure 2 is a horizontal section on line 2^a—2^a of Figure 1.

I claim:

The ornamental design for a bottle, as shown.

ARTHUR F. REED.
